[57] **CLAIM**

The ornamental design for a "putter head", as shown and described.

DESCRIPTION

FIG. 1 is a rear, right side perspective view of a putter head showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a left side view of a second embodiment of the putter head as disclosed in FIG. 1;

FIG. 9 is a right side view of the embodiment of FIG. 8; and, FIG. 10 is a top view of the embodiment of FIG. 8.

The undisclosed sides of the second embodiment of the putter head is identical to the first embodiment.

The broken line showing of a fragmented shaft is for illustrative purposes only and forms no part of the claimed design.
